Des. 67,578

UNITED STATES PATENT OFFICE.

WALTER CLARK, OF TORONTO, ONTARIO, CANADA.

DESIGN FOR A PORTABLE ELECTRIC HEATER.

Application filed March 15, 1924. Serial No. 8,947. Term of patent 14 years.

To all whom it may concern:

Be it known that I, WALTER CLARK, a citizen of the Dominion of Canada, residing at 81 Jarvis Street, Toronto, in the county of York and Province of Ontario, Dominion of Canada, have invented a new, original, and ornamental Design for Portable Electric Heaters, of which the following is a

specification, reference being had to the accompanying drawing, forming part thereof.

The figure is a plan view of a portable electric heater, showing my new design.

I claim:

The ornamental design for a portable electric heater, as shown.

WALTER CLARK.
